FIG. 1 is a front left side perspective view of a machine for automatically duplicating keys showing my new design.

FIG. 2 is a front right side perspective view thereof.

The top and bottom are plain and unornamented and the rear is likewise plain and unornamented except for the centrally located band-like element as seen in FIGS. 1 and 2.

I claim:

The ornamental design for a machine for automatically duplicating keys, substantially as shown and described.
